COLLAPSIBLE CONTAINER

Joseph W. Wallace, Richmond, Va., assignor to Reynolds Metals Company, Richmond, Va., a corporation of Delaware

Filed Mar. 29, 1960, Ser. No. 18,446

9 Claims. (Cl. 220—6)

This invention relates to collapsible containers and more particularly to an improved container of that type which is characterized by a lightweight side and bottom construction while at the same time incorporating a sturdy framework construction.

In the shipping and handling of various commodities, especially fresh fruit and vegetables, lightweight, collapsible containers which may be used repeatedly, are highly desirable, but at the same time require certain characteristics not needed in the ordinary container. For example, the container should not contribute to spoilage of fruit, as may occur when the fruit is bruised by projecting from the confines of the container, such as often occurs with open mesh containers, or is bruised by resting upon a solid unyielding surface, such as often occurs with heavy wooden or metallic containers. Moreover, since refrigeration is often employed in the handling of such commodities, the container construction preferably employs a material of good heat conductivity. It, therefore, is a purpose of the invention to make available a container which satisfies the requirements of users as above indicated.

An object of the invention is to provide a lightweight, collapsible container affording an improved protection to its contents during shipping and handling.

Another object is to provide a lightweight container whose bottom and side walls are sufficiently resilient to afford a cushioned holding effect upon the contents of the container.

Another object is to provide an improved container which is easily assembled without requiring welding, nailing, or special fastening means; which may be easily repaired without special tools and/or welding or soldering equipment or the like; which may be easily collapsed after use and which may be easily expanded for re-use; which may be readily cleaned and which is non-corrodible; and which possesses an attractive appearance.

Other objects and advantages will become more apparent as the description proceeds and when considered in conjunction with the accompanying drawings in which:

FIG. 1 is a plan view of the container in expanded form and ready for use;

FIG. 2 is a side elevation of the container of FIG. 1;

FIG. 3 is an end elevation of the container of FIG. 1;

FIG. 4 is a perspective view of the container of FIG. 1 shown in fully collapsed form and to a smaller scale;

FIG. 5 is a sectional view of a portion of one corner post taken on line 5—5 of FIG. 1 and to an enlarged scale;

FIG. 6 is a plan view of one typical bottom supporting spacer;

FIG. 7 is a sectional view of one side wall taken on line 7—7 of FIG. 2 and to a larger scale;

FIG. 8 is a sectional view of one side wall taken on line 8—8 of FIG. 2 and to a larger scale;

FIG. 9 is a sectional view of one end wall taken on line 9—9 of FIG. 3 and to a larger scale;

2

FIG. 10 is a sectional view of one end wall taken on line 10—10 of FIG. 3 and to a larger scale;

FIG. 11 is a sectional view of the bottom member taken on line 11—11 of FIG. 1 and to a larger scale; and

FIG. 12 is a sectional view of one handle taken on line 12—12 of FIG. 3 and to a larger scale.

In accordance with the invention an open top container is formed with a collapsible framework capable of providing the necessary container rigidity when the container is set up and which framework includes four vertical corner posts. Between adjacent posts a pair of upper and lower rigid spacers are mounted, each spacer having means at its ends which engage with the posts and permits the spacers to rotate partially around the post in a horizontal plane, thus giving an articulated framework construction. Two side and two end walls, each having integrally formed sleeves at each of its edges, are mounted between the respective adjacent posts. The sleeves of these walls engage with the adjacent posts as well as with the corresponding upper and lower rigid spacers between the posts. A bottom member likewise has integral sleeve portions along one of its edges and which sleeve portions engage with one of the lower spacers intermediate two adjacent posts. Preferably, one or more of the lower spacers, other than the one to which the bottom member is hinged, provides projecting portions which extend into the path of travel of the hinged bottom when the container is expanded for use and which thus serve to support that bottom in operative condition for container usage. Accordingly, the walls and bottom portions of the container may be somewhat flexible, dependence being made upon the post and spacer framework for rigidity of the filled container. Thin wall material may thus be employed in the container affording lightweight and reduced cost of construction.

Referring now to FIGS. 1 to 3, a typical expanded container embodying the invention may have a rectangular shape defined by a framework including corner posts 10, 11, 12, and 13. Each post is vertically arranged and may be formed of a tubular aluminum alloy extrusion preferably cylindrical in form and flared outwardly at each end. Adjacent the lowermost ends of the posts a pair of rigid rod-like spacers 15 and 16, one being shown in FIG. 6, are disposed, serving respectively to hold posts 11, 12 and posts 10, 13 apart, as well as to give rigidity to the framework. Each of these lower end spacers terminates at its ends in a substantially closed ring, as illustrated at 14 and 17, adapted to embrace the circumference of the respective post to which it is attached, but having a slip fit therewith permitting the spacer to rotate in a horizontal plane about that post as a pivot. Moreover, each of these lower end spacers includes one or more projecting portions 18 and 19 which extend inwardly of the container and serve a purpose later to appear.

A pair of rigid upper end spacers 20 and 21 provided with similar interrupted ring-like ends, but without the intermediate inwardly projecting portions, rotatably engage with the respective corner posts 11, 12 and 10, 13 near the upper ends of those posts.

In addition, a pair of rigid lower side spacers 22 and 23, of the same type as described, and located as seen in FIG. 3, having similar interrupted ring-like ends, rotatably engage with the respective corner posts 12, 13 and 11, 10 adjacent the lower ends of those posts and

serve to hold those posts at a spaced distance apart and to give rigidity to the framework. Finally, a pair of rigid upper side spacers 24 and 25 of the same general type having interrupted ring-like ends, rotatably engage with the respective corner posts 11, 10 and 12, 13 adjacent the upper ends of those posts and complete the structure of the framework. Each of the above-described spacers may, for example, comprise an extruded aluminum rod of about 0.25 inch diameter thus possessing sufficient tensile and compression strength to form, in combination with the corner posts, a strong but light-weight framework for the container. The corner posts, however, have a larger diameter than the spacer rods thus requiring larger diameter sleeves for engagement with those posts than for engagement with those rods.

Considering now FIGS. 3, 9 and 10, one end wall or skin member 30 of the container is shown and may comprise a sheet of aluminum alloy having a thickness of about 0.032 inch, thus representing an extremely light weight in contrast to walls of usual containers. A plurality of vertically extending outwardly bulging ribs shown at 31, 32 and 33 may be formed integrally in the skin member 30 to afford additional rigidity therefor. The curled lower edge may include spaced portions 35, 35A, and 35B with the spaces therebetween being large enough to accommodate the projections 18 and 19 of the lower side spacer 15. The end wall member 30 also includes a curled upper edge 34 nesting securely around the upper end spacer 20. This curled upper edge may be interrupted near the center of the wall to provide an open space 36 suitable for a hand hold. Within this space a separate hollow handle 37 (FIGS. 3 and 12), may be arranged around the upper spacer 20 with a diameter consistent with ease of handling and with the desired collapsibility of the container.

The end wall or skin 30 also includes along one of its vertical edges the larger curled portions 38 and 39 spaced from each other and serving as mounting sleeves rotatably engageable with the corner post 12. Also along its other vertical edge the similar curled portions 40 and 41 (FIG. 3) rotatably engage with the corner post 11.

In a similar manner, the opposite end wall or skin 42 of like material is provided with an opening at its upper edge housing the handle 43, with curled upper edge portions 44 nesting securely around the upper end spacer 21, with lower curled edge portions nesting securely around the lower end spacer 22, and with vertical edge curled portions serving as mounting sleeves rotatably engageable with the corner posts 10 and 13.

Referring now to FIGS. 2, 7 and 8, one side wall or skin member 50 of the container is shown and may comprise a like sheet of thin aluminum alloy with a plurality of vertically extending outwardly bulging ribs 51 to 58, inclusive. Along its upper edge the member 50 may have a single curled sleeve 59 to receive the upper side spacer 25 in securely nested relation therealong. Along its lower edge it may have a plurality of curled sleeves 60 to 65, inclusive, spaced from each other and receiving the lower side spacer 22.

At its vertical edges the member 50 is provided with curled integral sleeve portions 66, 67, 68 and 69, 70, 71, respectively, rotatably engageable with corner posts 13 and 12 and in interleaved relation to the sleeves of the end wall members which engage with those same posts.

Similarly, the other side wall or skin member 75 of like material is provided with a plurality of vertically extending outwardly bulging ribs; with a single curled sleeve at its upper edge receiving the upper side spacer 24; with a curled sleeve at its lower edge receiving the lower side spacer 23; and with curled sleeve portions at each of its vertical edges rotatably engaging the respective corner posts 10 and 11 and being spaced from each other along those posts and in interleaved relation

to the sleeves of the end walls which engage with those same posts.

Considering now FIGS. 1 and 11, a bottom member 80 of similar aluminum material is provided with an upwardly facing peripheral edge 81 along one side and along both ends and with interrupted upwardly facing edges 82 along the side at which the bottom member is pivotally mounted. A plurality of horizontally extending outwardly bulged transverse ribs 83 to 93, inclusive, are formed in the bottom member and serve to strengthen the same. Along the pivot side of the bottom member a plurality of integral sleeve portions 94 to 98, inclusive, rotatably surrounding and engaging the lower side spacer 22 are disposed, these sleeve portions alternating with the sleeve portions 60 to 65 of the side wall 50 in their engagement with that lower side spacer. The side of the bottom opposite the pivot side thereof approaches closely the side wall 75 of the container when the bottom member is moved into a horizontal plane and thus the rigidity of the framework and container is established even though the container may be later readily collapsed as now to be described.

Referring to FIG. 4, the collapsed container requires only a small storage space, and when ready for use, the operator merely grasps it by handle 37 and turns the container into an upright position. Thereafter, by moving corner posts 12 and 10 toward each other until a rectangular container shape is formed, the bottom 80, which has been housed between side walls 75 and 50 of the collapsed container then is free to pivot downwardly about spacer 22 and into a horizontal plane. As it does so, its opposite ends come to rest upon the projections 18, 19 of the lower end spacers 15 and 16 and its side edge 81 comes to rest in contact with the lower portion of the side wall 75. During this expansion, the several vertical sleeve portions of the end walls or skins 30 and 42 and of the side walls or skins 50 and 75 have rotated about the corner posts with which they engage, as have the interrupted ring ends of the several spacers of the framework.

With the foregoing in mind, an important advantage of the invention will now become apparent. As the expanded set-up container is loaded, as with perishable fruit or vegetables, the weight of the contents will be exerted against the thin bottom and thin walls or skins. Each of these elements is securely supported upon the rigid framework formed by the spacers and corner posts, but at the same time may flex outwardly to a limited extent due to the described sleeve construction. This flexing or resiliency provides an important cushioning effect for the contents and assists in reducing the bruising and subsequent spoilage when fruit or the like is being handled. As is apparent, the interrupted ring-like nature of the sleeves permits a small amount of relaxing of the grip of the walls or bottom upon the posts or spacers as pressure is applied to the inner surfaces of these walls or bottom, since the contact of the partially open sleeve portions with the posts and spacers is of a non-rigid nature. However, upon relief of this pressure, the sleeves again assume their securely nested relation upon these elements of that framework.

It is to be understood that although the ribs 83 through 93 are illustrated as extending in a direction transverse to the longitudinal axis of the bottom member 80, they may be parallel to the longitudinal axis. The latter configuration is advantageous in transporting the box along a roller type of conveyor.

For the purpose of stacking a plurality of filled containers and to prevent the ribs on the bottom of an upper container from pressing upon the contents of a lower container, a suitable spacing plug, as best seen in FIG. 5, may be employed. At least two such spacer plugs mounted on diagonally disposed corner posts are employed, but three or even four such spacer plugs may be used, if desired. Each such spacer plug includes a solid

member 100, such as an aluminum casting having an intermediate peripheral shoulder 101, and is of a generally cylindrical shape. Each corner post is formed with slightly flared upper and lower ends terminating in curled flanges, one being seen at 102 for the corner post 10 in FIG. 5 as an example. The lower part 103 of the plug is suitably shaped to engage within the upper end of the hollow corner post with a snug fit and to extend well below the plane at which the ring ends of the spacer rods, here shown as rods 16 and 24, are located. If desired, the corner post may also have a circumferential crimp, not shown, engaging with the lower part of the spacer plug. The upper part 104 of the spacer plug also is shaped so as to engage with a snug fit with the lower end of the corner post of another container which is to be mounted above the described container. As will thus be seen, the upper flange 102 of a given post will abut against the lower surface or shoulder 101 of the spacer plug associated with that container while the lower flange of a given post on another container to be stacked upon the first container will in turn abut against the upper surface of shoulder 101. Because of the flanged nature of the lower end of the post, however, the stacked containers can be readily disengaged from each other.

While aluminum alloy has been referred to as a preferred material in the all-metallic structure above described, it will be obvious that the invention is not limited to that one material. However, it is preferred for usage when citrus fruits or the like are to be housed within the container. Aluminum, as well known, is non-corrodible when in contact with the acids of such fruit; may be readily cleaned as by steam or the like when the container becomes dirty through handling; is light weight; serves as an excellent heat transfer material when refrigeration is applied to the contents of the container; and presents an attractive appearance when the container is to be employed at point of sale. Additionally, because of the low emissivity of aluminum, the container remains cool for a long period of time after the refrigeration has been discontinued.

Having thus described the invention, it will be understood that a particular embodiment thereof has been shown and that the invention is not limited to that one embodiment, since many modifications can be made, and it therefore is contemplated by the appended claims to cover any such modifications as fall within the true scope and spirit of the invention.

What is claimed is:

1. A container comprising, a collapsible framework including first, second, third and fourth cylindrical corner posts having an outwardly flared flange at each end, a pair of rigid upper and lower spacers disposed between each of the adjacent corner posts and attached to said posts respectively inboard of said flanges, each spacer having a ring-like means at its ends surrounding the respective posts for rotation of the spacers in a horizontal plane around said posts whereby said framework may be selectively collapsed and expanded by moving diagonally arranged posts from and toward each other; first, second, third and fourth wall members mounted between the respective posts with each member having substantially cylindrical sleeve means at each of its vertical edges engaging with the respective posts for rotation thereabout and with substantially cylindrical sleeve means at each of its horizontal edges engaging with the respective pair of spacers, each member engaging its respective pair of corner posts at the same points on said respective pair of corner posts, each member being movable with the respective pair of spacers on which the member engages, said wall members having flexible surfaces, and a bottom member having substantially cylindrical sleeve means along one edge engaging with one of said lower spacers and pivotally movable into a vertical plane when said container is collapsed and into a horizontal plane when said container is expanded.

2. A container as defined in claim 1 wherein two of said lower spacers located opposite each other include projections extending inwardly of said container and into the path of movement of said bottom member when said container is expanded thereby to provide a support for two edges of said bottom member, said projections lying between the sleeve portions of the respective walls attached to the respective spacers on which said projections are located.
3. An open-top container having flexible side walls and comprising, a collapsible framework, including first, second, third and fourth vertical cylindrical corner posts, a pair of rigid upper and lower spacers disposed between each of the adjacent corner posts and attached to said posts respectively adjacent the tops and bottoms of said posts, each spacer being of cylindrical rod shape and having means at its ends engaging the respective posts for rotation of the spacers in a horizontal plane around said posts whereby said framework may be selectively collapsed and expanded by moving diagonally arranged posts from and toward each other; first, second, third and fourth wall members of a material and thickness commensurate with limited outward flexing of said members upon application of pressure to the interior surface thereof and mounted between the respective corner posts with each member having substantially cylindrical sleeve means at its vertical edges engaging with the respective posts for rotation thereabout and for non-rigid contact therewith, and substantially cylindrical sleeve means at its horizontal edges engaging with the respective pair of spacers and for non-rigid contact therewith; each member engaging its respective pair of corner posts at the same points on said respective pair of corner posts; each member being movable with the respective pair of spacers on which the member engages, and a bottom member having substantially cylindrical sleeve means along one edge engaging with one of said lower spacers in non-rigid contact therewith and pivotally movable into a vertical plane when said container is collapsed and into a horizontal plane when said container is expanded, one edge of said bottom being in contact with the wall member located opposite said one of said lower spacers when the container is expanded.
4. A container as defined in claim 3 wherein at least two oppositely disposed wall members include vertically arranged outwardly bulged ribs integral therewith.
5. A container as defined in claim 3 wherein the diameter of said posts is larger than the diameter of said spacers.
6. A container comprising: a collapsible framework including first, second, third and fourth corner posts; four pairs of upper and lower spacers disposed between and pivotally attached to adjacent corner posts; and first, second, third and fourth wall members mounted between the respective corner posts, each wall member being pivotally secured to its adjacent pair of corner posts and to the upper and lower spacers secured to that pair of corner posts, each wall member engaging its respective pair of corner posts at the same points on said respective pair of corner posts.
7. A container as set forth in claim 6 wherein a bottom member is secured to one of said lower spacers.
8. A container as set forth in claim 6 wherein each corner post is hollow and has outwardly directed flanges at the opposed ends thereof, said flanges being disposed outboard of said spacers.
9. A container as set forth in claim 8 wherein a plurality of plugs are disposed in the top ends of certain of said corner posts, each plug having opposed conical portions defining an outwardly directed medial flange therebetween, each plug having one conical portion thereof disposed in its respective corner post and having its flange engaging the flange of that corner post whereby another container can be disposed on top of the first-named container with the other conical portions of said plugs received in the lower ends of the corner posts of the other

container to space the other container from the first-named container.
